UNITED STATES PATENT OFFICE.

CHARLES H. COOLEY, OF HARTFORD, CONNECTICUT, ASSIGNOR TO THE PRATT & WHITNEY COMPANY, OF SAME PLACE.

GRAIN-WEIGHER.

SPECIFICATION forming part of Letters Patent No. 447,715, dated March 3, 1891.

Application filed July 14, 1890. Serial No. 358,643. (No model.)

To all whom it may concern:

Be it known that I, CHARLES H. COOLEY, a citizen of the United States, residing at Hartford, in the county of Hartford and State of Connecticut, have invented certain new and useful Improvements in Grain-Weighers, of which the following is a specification.

This invention relates to automatic grain-weighers, and has for its object to furnish improvements in the bucket mechanism of the grain-weigher.

My present improvements are intended for use in connection with grain-weighers of the class described in Letters Patent No. 442,723, granted to me December 16, 1890, to which reference may be had for such parts of the grain-weigher as are not herein fully described.

In the drawing accompanying and forming a part of this specification is shown a side elevation, partly in section, of a grain-bucket mechanism embodying my present improvements.

For convenience of reference the several parts are herein designated by the same reference-characters as are used to designate the corresponding parts in said prior application.

The numeral 19 designates one of the bucket-supporting arms of the scale-beam, which arm is furnished with the usual knife-edge 15 for carrying the hanger 16, whose upper end is shaped substantially as shown for suspension on said knife-edge. The grain-bucket G is journaled in the hangers at 12 in bearings formed in the hangers. At its lower end the bucket has two passage chutes or spouts 34 and 36, respectively, for the two compartments of the oscillating double-chambered grain-bucket G, whose chambers are divided by a central partition-wall 8, whose lower edge may be bifurcated and terminate in the two edges 4 and 6, respectively.

The hanger 16 extends below the pivot 12, and is there divided into arms, as 10 and 11, which extend to the lower end of the bucket-spout and there carry the bucket-closers 33 and 35 for the spouts 34 and 36, respectively. Between the bucket-spout and its closer there is a considerable space 57 sufficiently large to prevent kernels of grain from wedging there-

in. The inner side of the spout 4, when the spout is swung over the closer, as at the left hand of the figure - drawing, comes down close to the closer, as there shown, and thus 55 prevents the escape at that point of the grain which lies in the spout and on the closer. On the outer edge of the closer a fixed rim 73 is provided as a guard for preventing overflow at that point, also rims, as 52 and 54, at the 60 ends of the closer.

According to my present improvements the flat closer 33 is set oblique to the line of movement of the spout over a closer, so that as the bucket moves in the direction of the arrow a 65 the edge 4 will approach the lower edge 3 of the closer 33 at a considerable angle, substantially as shown, so that on the reverse movement of the bucket said wall 4 leaves said edge 3 gradually and with a constantly-widening space between them from the very instant of the opening movement, thus preventing on the opening of the bucket any possibility of wedging the split and wedge-shaped kernels of grain between the two edges 3 and 4. In 75 order to extend this principle of operation to the entire width of the spout, and thus render very certain the proper action of the spout and closer, I form the upper line of the closer at right angles to a line from the axis 12 80 through the closer beyond the spout 34, said line being radial to the axis 12 and designated by b b. With the axis 12 as a center, draw now the line c c, touching the surface of the plate 33 at a point substantially coincident with the outer or upper edge thereof just beyond the outer wall 2 of the spout 34. The upper surface of the plate 33 is now tangential to the circle c c at the intersection of said circle with the line b b. If now the spout 34 90 be swung toward the right, the points of the lower end of said spout will, owing to the construction set forth, move laterally and upwardly from the plate 33, thus avoiding, as above set forth, the liability of clogging on 95 the opening movement.

By making the line of the closer-plate tangential to the point specified the required "relief" between the spout and closer is obtained for preventing any clogging of the grain between them on the movement of the bucket from over the closer, the closer-plate still be-

ing at such an angle to the vertical as will permit the grain to run freely off from it, and in such relation to the bucket-axis as prevents the weight or pressure of the grain thereon 5 from tending to move the bucket.

It will of course be understood that the closer 35 and spout 36 are or may be constructed upon the same principle, but oppositely disposed to the vertical plane through 10 the axis 12 and the knife-edge 15.

Having thus described my invention, I claim—

- 15 1. In a grain-weigher, the combination, with the bucket-supporting hangers and with the oscillating bucket carried in said hangers and having discharge-spouts, substantially as described, of the closer-plate carried by the hangers and set tangential at a point substantially coincident with the upper side of the 20 closed spout to a circle concentric with the bucket-axis, the lower edge of the closer being contiguous to the lower side of the closed

spout, whereby the spout begins at once to open for the free discharge of the grain on the beginning of the bucket movement. 25

2. In a grain-weigher, the combination, with the hangers and the oscillating double-chambered grain-bucket supported thereby and having oppositely-disposed discharge-spouts, substantially as described, of the two oppositely-disposed bucket-closers, each set inclined, substantially as shown, tangential to the circle concentric with the bucket-axis, the lower edges of the closers being contiguous to the lower side of the closed spouts, whereby 30 the spouts begin at once to open for the free discharge of the grain on the beginning of the bucket movement, the whole being constructed to close one spout simultaneously with the opening of the opposite spout. 35

CHARLES H. COOLEY.
